CLAIM

I claim the ornamental design for a curved canopy lounge, substantially as shown and described.

DESCRIPTION

FIG. 1 is a frontal view of a curved canopy lounge, embodying the new design, the rear view being the same;

FIG. 2 is a top plan view of the FIG. 1 design;

FIG. 3 is a bottom plan view of the FIG. 1 design; and,

FIG. 4 is a left side elevation view of the FIG. 1 design, the right side elevation being the same.
